F. P. PEACE & J. W. D. WILLIAMS.
Magazine Fire-Arms.

No. 146,611.

Patented Jan. 20, 1874.

UNITED STATES PATENT OFFICE.

FRANK P. PEACE, OF MARYSVILLE, AND JAMES W. D. WILLIAMS, OF KNOXVILLE, TENNESSEE.

IMPROVEMENT IN MAGAZINE FIRE-ARMS.

Specification forming part of Letters Patent No. **146,611**, dated January 20, 1874; application filed November 1, 1873.

To all whom it may concern:

Be it known that we, FRANK P. PEACE, of Marysville, in the county of Blount and State of Tennessee, and JAMES W. D. WILLIAMS, of Knoxville, in the county of Knox and State of Tennessee, have invented a new and useful Improvement in Breech-Loading Fire-Arms, of which the following is a specification:

Our invention consists of a magazine-chamber on each side of the barrel with a transversely-reciprocating block behind them for taking the cartridges from said chambers alternately and presenting them to the barrel, also for removing the shells to a discharger, said block being worked by a crank-shaft and connecting-rod set in motion by a trigger-wheel, which is turned far enough each time it is pulled for firing to effect one movement of the block, which brings the cartridge into position just before the hammer falls.

The object is to provide a simple and efficient repeating arm which can be loaded and fired simply by pulling the trigger.

Figure 1 is a longitudinal sectional elevation of our improved gun on the line $x-x$ of Fig. 2. Fig. 2 is a horizontal section. Fig. 3 is a front elevation. Fig. 4 is a cross-section on the line $y-y$ of Fig. 1, looking toward the muzzle; and Fig. 5 is a cross-section on the same line looking toward the breech.

Similar letters of reference indicate corresponding parts.

We have a chamber, a , on each side of the barrel b , for containing cartridges, with a spring for forcing them down into the double-chambered block E , which is to slide first one way and then the other to receive the cartridges alternately from the opposite chambers and present them to the barrel, removing the fired shell at the same time. The block is to be shifted by the trigger C , which acts upon said block through the medium of wheels A , B , disk D , and connecting-rod J . The trigger, turning wheel A , turns B , and B turns D , which is connected by the rod J with the sliding block E , said rod being connected to the disk at b . The block slides back and forth at each revolution of the pit-

man wheel or disk D . The holes in the block exactly correspond with the holes in the chambers and the barrel; also, with one of the holes in block I . The holes in block I receive the discharged cartridges, which are pushed into them by the cartridges entering block E , and which, by means of a weak spring, g , in the bottom of the holes, are discharged through the hole L in plate K .

The trigger C touches hammer F precisely at the same time that cog-wheel A touches cog-wheel B , causing it to strike needle G , which works through the small hole in the center of block I and fires the cartridge H , which is brought into position just before the hammer strikes. The barrel has a joint at M , on which it swings when the plate N , which is hinged at O , is raised, said plate being held down by swing-catches P . Another plate, Q , similarly hinged on the top, affords access to the working parts for taking the gun apart and putting it together as readily as a common gun can be loaded.

The loading and firing are effected merely by the pulling of the trigger.

In this example a coiled spring, R , is represented as the mainspring; but it will probably in practice be changed for the ordinary flat spring.

We shall probably have some little cut-off devices attached, so as to be adjusted to keep the discharged shells in the discharger when the gun is not to be fired, to prevent the cartridges from being presented to the barrel by the pulling of the trigger. And we shall probably have some small springs attached to the sliding block for preventing the cartridges from being driven into the barrel by the hammer without being fired. And we shall also have a little plate or plates between the breech-block and the shifting-block to prevent the cartridges from going back into the dischargers before the first fire, in case the dischargers be empty, said plate or plates to be removed after the first fire.

Having thus described our invention, we claim as new and desire to secure by Letters Patent—

1. The combination of two chambers, a , a

transferring-block, B, and mechanism for actuating the latter through the medium of the trigger, so that the loading and firing will be accomplished merely by the pulling of the trigger, substantially as specified.

2. The combination of discharging-block I and springs *g* with the reciprocating block E, for discharging the shells, substantially as specified.

3. The combination and arrangement of the trigger with the hammer and the mechanism, substantially as described, for actuating the transferring-block, as specified.

FRANK P. PEACE.

JAMES W. D. WILLIAMS.
